OSCILLATION GENERATOR

Browder J. Thompson, East Orange, N. J., assignor to Radio Corporation of America, a corporation of Delaware

Application April 29, 1933, Serial No. 668,522

9 Claims. (Cl. 250—36)

My invention relates to oscillation generators of the thermionic vacuum tube type, and more particularly to an improved high frequency generator of this type capable of generating relatively strong electric waves of a length less than one meter, and also to an improved thermionic tube suitable for use in the generation of high frequency oscillations and for other purposes.

The lower limit on the length of the electric waves produced by an electron discharge type of oscillation generator with regenerative coupling is reached when the duration of travel of the electrons in the tube during each cycle of the generated frequency becomes appreciable in comparison with the duration of the cycle, whereupon the conditions suitable for regenerative coupling are no longer present so far as the phase relation of the grid and anode alternating potentials are concerned. With the vacuum tubes now in general commercial use, the shortest waves that can be obtained with regenerative coupling have a length of approximately one meter, and are so weak that they are useful only for measuring purposes. Waves shorter than one meter can be produced with a three electrode vacuum tube by the Barkhausen and Kurz method, by applying a negative potential of about 10 to 20 volts to the plate electrode, and a positive potential of a few hundred volts to the grid which then becomes the anode.

According to Barkhausen and Kurz the high velocity electrons pass through the meshes of the highly positive grid electrode, stop and turn back in the retarding field of the negative plate electrode, go back through the grid towards the cathode, stop in the retarding field of the cathode, and turn back toward the grid. The electrons, therefore, oscillate about or swing back and forth through the grid producing high frequency oscillations which will appear in an oscillating circuit connected to the grid and the plate electrode. The frequency of these oscillations is determined by the time of travel of the electrons through the inter-electrode space and consequently depends upon the electrode spacing and the applied potentials.

Gill and Morrell have found that the same arrangement which produces the Barkhausen-Kurz oscillations may be used to generate waves of a length which is determined, not by the electrode spacings and potentials alone, but also by the tuning of an associated oscillating system, usually connected to the grid and plate electrodes of the tube. These two types of oscillation, one depend-

ent solely on electrode spacing and applied potentials, and the other also dependent on the tuning of an oscillating circuit, may be produced independently or even simultaneously by the same tube by adjusting the associated circuits.

The only type of tube which, so far as applicant is aware, has heretofore been successfully used as above described to generate ultra high frequency oscillations is the cylindrical type with the electrodes coaxial with a straight cathode. Shorter waves can be obtained by increasing the potentials or reducing the electrode spacing, but the extent to which the electrode spacing in the cylindrical type of tube can be reduced by decreasing the diameter of the electrodes is limited rather definitely by various difficulties, such as objectionable overheating of a small diameter grid electrode when it is used as an anode at high potential, so that in general the usefulness and utility of such a tube tends to decrease as the diameter of the electrodes is reduced. In this respect a flat type of tube with flat electrodes and a flat cathode, such as a V or M shaped filamentary cathode of the usual type and dimensions and with its strands in a plane parallel to the other electrodes, would theoretically have some advantages, but heretofore the production of ultra high frequency oscillations and ultra short waves with a tube having the usual V or M filamentary cathode and particularly with a flat type of tube, has been considered impossible.

One object of my invention is to provide an improved oscillation generator of the thermionic vacuum tube type of a relatively high output and capable of generating oscillations, particularly ultra high frequency oscillations for producing the electric waves shorter than one meter which are commonly referred to as ultra short waves. Another object is to provide a thermionic vacuum tube of the flat type particularly suitable for use as an ultra high frequency generator, and also useful for other purposes.

The novel features which I believe to be characteristic of my invention are set forth with particularity in the appended claims. My invention itself, however, will best be understood by reference to the following specification taken in connection with the accompanying drawings, in which Fig. 1 is a perspective view, with parts broken away, of the mount of a flat type of tube embodying my invention; Fig. 2 is a horizontal cross section of Fig. 1 on the line 2—2; Fig. 3 is a similar horizontal cross section of a modification of the mount shown in Fig. 1; Fig. 4 is

a perspective view, with parts broken away, of another modified form of tube; Fig. 5 is a horizontal cross section of Fig. 4 on the line 8—5; Fig. 6 is a diagram of a circuit for using a tube embodying my invention as an ultra high frequency generator; Fig. 7 is a diagram of a circuit for using the tube as a modulator; and Fig. 8 is a diagram of a circuit for the tube shown in Fig. 4.

In the particular embodiment of my invention shown in Fig. 1 the electrodes of the tube are enclosed in a highly evacuated bulb not shown in the drawings, but indicated by the circles in Figs. 6 to 8. The electrodes are mounted on the usual stem 15 sealed into the bulb and having a plurality of projecting electrode supports 16 connected to leading-in wires in the stem. The mount shown in Fig. 1 comprises a flat plate-like electrode 17, preferably a sheet of metal bent at the edges as illustrated and secured to a pair of the supports 16; a grid-like electrode 18 made, like the usual grid, of transverse grid wires secured to two parallel side rods; and a filamentary cathode of the usual M shape, and consisting of two loops 19 mounted in the same plane and electrically connected in parallel. These three electrodes are substantially flat and are mounted side by side in parallel planes, as in the usual flat type of three electrode filamentary cathode tubes. The three electrodes are rigidly spaced by an insulating spacer, such as a glass bead spacer 20 having projecting studs 21 secured to the upper ends of the plate supports and of the side rods of the grid-like electrode 18 and also having two filament hooks 22 for holding the bights of the filament loops in position. The filament may be approximately of the dimensions of the filamentary cathodes used in commercial tubes, and a suitable filament drop in each of the loops is, for example, about 3½ volts.

In accordance with my invention I mount behind the cathode on the side opposite the grid-like electrode 18 an auxiliary or backing electrode, such as a plate-like electrode 23, which may conveniently be made of sheet metal bent up at the edges to form flanges 24 which, as shown in Figs. 1 and 2, extend inside the edges of the electrode 17. This auxiliary electrode may be mounted on a pair of the supports 16, as shown in Fig. 1. The grid-like electrode 18 is substantially the usual grid with one side removed, and the external electrode 17 is substantially half of the flat or box type plate electrode commonly used in commercial tubes. Structurally the tube resembles the usual flat type three electrode tube having a filamentary M shaped cathode, with the grid and plate at one side or in front of the cathode, and, in addition, an auxiliary electrode or backing plate 23 coextensive with and behind the filamentary cathode, and in a plane parallel to the plane of the cathode.

When the tube shown in Fig. 1 is connected in a Barkhausen-Kurz oscillation circuit, as shown in Fig. 6, the grid electrode 18 is at a highly positive potential and becomes the anode, and the electrode 17 in front of the anode is at a lower positive or even somewhat negative potential, so that it acts primarily as a limiting electrode to produce parallel to said cathode and anode an equipotential region of substantially the same potential as said cathode for limiting the extent of travel of the electrons through the grid-like highly positive anode 17. The term potential is used in this application in the usual sense and means potential with reference to the cathode, which is considered a point of zero

potential and with reference to which the other electrodes may be positive or negative. If the backing electrode 17 were absent, the tube would not operate as a Barkhausen-Kurz oscillator, possibly because the potential in the region or space adjacent and in the plane of the cathode, and particularly in the space between the sides of the loops 19 of the cathode, is positive, since the potential of this space is the resultant of the effects of the cathode and of the highly positive grid-like anode 18.

In accordance with my invention I have provided means, such as the negative auxiliary or backing electrode 23 behind the cathode by which this positive potential of the region in the plane of the cathode, and especially of the space between the sides of the loops of the filamentary cathode, may be counteracted to any desired extent. The auxiliary electrode may be made sufficiently negative to lower this space potential to the point where the tube will produce high frequency oscillations. I have found that when associated with suitable circuits a tube constructed as shown in Fig. 1 will produce relatively strong ultra high frequency oscillations. The tube may conveniently be made with an M shaped thoriated tungsten filament activated to have high emission and consisting of the two V shaped loops 19 connected in parallel each loop being about 5 mm. wide at the open end, and having a filament drop of about 3½ volts and a filament current of about 1.25 amperes. The anode 18 may be made like a grid of 5 mil grid wire with 35 wires per inch. The electrode spacing may be about 1 mm. between the auxiliary electrode 23 and the cathode; 1.5 mm. between cathode and anode 18; and 1.5 mm. between the anode and the limiting electrode 17. Such a tube may be operated with the grid-like anode 18 at about 250 volts positive, the limiting electrode 17 somewhere near zero potential, and the auxiliary or backing electrode 23 at from 5 to 20 volts negative.

While I do not wish to be limited by any particular theory of operation, it seems probable that this negative auxiliary or backing electrode counteracts the effects of the highly positive grid electrode 17 in the vicinity of the cathode and in the space between the sides of the loops 19 to such an extent that the space potential of the region adjacent the cathode and in the plane of the filamentary cathode is approximately the same as the potential of the sides of the loops, thus producing in effect an approximation to an equi-potential surface in the plane of the filamentary cathode. Such an equi-potential surface may, in conjunction with the electrodes, cause the time of travel of the electrons to be about the same on each side of the grid electrode, and hence cause the conditions in the tube to be favorable for the development of ultra high frequency oscillations.

The spacing of the grid-like anode and the cathode with spaced sections should be either approximately the same, or less than the interspacing of the cathode sections. In the particular tube shown in Fig. 1 the interspacing of the filamentary sections is the average distance between the sides of the V shaped loop of the filament. The spacing of the anode and the limiting or fronting electrode should be substantially equal to or greater than the spacing of the anode and the cathode. The spacing of the auxiliary or backing electrode and the cathode depends to some extent on the negative voltage applied to

the auxiliary electrode, and is not particularly critical.

By my invention it is feasible to make an ultra high frequency tube of the flat type with a single straight cathode, or with a filamentary cathode having its sides or electron emitting portions spaced quite far apart. As a result of my invention some serious limitations which have heretofore hampered the design and limited the out-
10 put of vacuum tubes for producing high frequency oscillations are greatly lessened. For example, in tubes used for producing Barkhausen-Kurz oscillations the grid-like anode operates at high potential, and may reach a brilliant white heat
15 due to electron bombardment. When the cylindrical type of tube is used for generating these oscillations the cathode emission is a rather critical factor, and since the grid-like anode is very close to the cathode, the heat radiated from a
20 very hot grid-like anode may affect the temperature and seriously modify the emission of the cathode, particularly of a high emission low temperature cathode, such as a thoriated tungsten filament or oxide coated cathode which normally
25 operates at a dull red heat and is relatively sensitive to temperature. In a tube embodying my invention such low temperature cathodes may be used, as I have found that in my tube the cathode emission is not critical and may be varied between wide limits without adversely affecting the operation of the tube. Other general advantages are obtained because the anode may be designed to have good radiation and to operate at a comparatively low temperature.

35 The auxiliary or backing electrode 23 need not be in the form of a plate or sheet of metal, nor need it be flat. It may, as shown in Fig. 3, be curved, or otherwise shaped so that the potential in the plane of the filament will approximate an equipotential surface at a somewhat lower negative potential on the auxiliary electrode than is required when the auxiliary electrode is flat. One advantageous shape is that shown in Fig. 3, where the auxiliary electrode has on its surface and in registry with the interspaces between the adjacent electron emitting sections of the cathode projections 25 which come closer to the plane of the filament than the other parts of the electrode surface which are in registry with the cathode sections themselves.

Fig. 4 is an embodiment of my invention in a tube having a straight cathode associated with a coplanar auxiliary electrode. In this tube the limiting electrode 26 is made like the plate electrode and the perforated anode 27 is made like the grid of the commercial tubes having the flat type of mount. The cathode may have one or more straight electron emitting sections, and in this particular tube consists of two straight electron emitting sections or filaments 28, positioned side by side in a plane coaxial with the electrodes 26 and 27, and shown connected in parallel, although they may be connected in series if desired. These filaments 28 are secured at their lower ends to a pair of the supports 16, and supplied with current by one of the supports, and at the upper ends are connected by a conductive jumper 29. A current supply lead 30 is connected through a flexible connector to the upper end of one of the filaments. The filaments are supported at their upper ends by resilient filament supports 31 projecting from a bead spacer 32, which also spaces the other electrodes by means of projecting studs 33.
55 The auxiliary electrode is close to and preferably

in the same plane as the cathode so as to affect the potential of the space adjacent the cathode. In the tube shown the auxiliary electrode consists of three flat strips 34, mounted coplanar with the filaments 28 and connected at their upper end by a conductive jumper 35, and held in position by a pair of the supports 16 and by the bead spacer 32.

5 In this particular form of tube the filaments 28 and the auxiliary electrode are coplanar and positioned coaxial of the electrodes 26 and 27, so that the mount of the tube is symmetrical. The potential of the region on each side of each filament 28 can be affected by the potential applied to the adjacent strips 34. As the edges of the 10 strips are quite close to the filaments, each filament has a strip of the auxiliary electrode on each side and close to it, and is in effect in a slot in the auxiliary electrode.

I have found that a tube constructed as shown 20 in Fig. 4 with straight filaments 28, each having a filament drop of about 3 volts, and connected in circuit as shown in Fig. 9, will produce ultra high frequency oscillations with a positive potential of about 250 volts on the electrode 27, and a potential on the auxiliary electrode strips 34 of about 2 volts positive, which is approximately the mean or average potential of the filaments. Under these conditions there probably exists in the immediate vicinity of the filaments and in the plane of 25 the filaments and the auxiliary electrode an equi-potential region of approximately the average potential of the cathode.

Fig. 6 is a diagram of a circuit by which the tube of Fig. 1 may be used to generate high frequency oscillations. In Fig. 7 the tuned output circuit of the generator is shown as a Lecher system tuning circuit connected to the grid-like anode 18 and the limiting electrode 17, and having two parallel wires 39 and 40 bridged by a 30 movable bridge 41 in which is a blocking condenser 42. The anode wire 39 and the limiting electrode wire 40 of the Lecher system are connected through inductances 43 to the battery 44 and to the cathode 19 respectively. This tuned 35 output circuit need not be connected exactly as shown, as it may be associated with the tube in other ways and with other electrodes of the tube, as is well understood in the art. Other types of resonant or tuned output circuits may also be 40 used.

Fig. 7 is a diagram of a circuit for using the tube of Fig. 1 as a modulator. The circuit is much the same as in Fig. 6, but with the inductances 43 placed at the ends of the bridge 41, and an 45 input circuit, comprising an input transformer 45, connected to the auxiliary electrode 23.

Fig. 8 is a diagram of the tube of Fig. 4 connected in a circuit similar to Fig. 6. With a positive potential of 250 volts on the anode, and a positive potential of 2 to 2½ volts on the auxiliary electrode 34, ultra high frequency oscillations are generated and appear in the output circuit.

While I have shown and described a preferred embodiment of my invention, I do not wish to be limited to this particular form, as devices constructed in accordance with the principles of my invention may be made in various forms and modifications without departing from the scope 65 of my invention as set forth in the appended claims.

What I claim is:

1. An oscillation generator comprising an electron discharge tube having a thermionic cathode 70

- with spaced electron emitting sections mounted side by side in the same plane, a perforated anode parallel to the plane of said cathode, a limiting electrode in front of said anode opposite said cathode and spaced from said anode a distance at least equal to the spacing between said anode and said cathode, a backing conductor parallel to and in operative juxtaposition to the electron emitting sections of said cathode, a source of potential with reference to said cathode for impressing a high positive potential on said anode, a potential approximately that of said cathode on said limiting electrode, and on said backing conductor a potential which makes the space potential between the parallel sections of said cathode substantially the same as the potential of said sections, and a tuned output circuit including said anode.
2. An oscillation generator comprising an electron discharge tube having a perforated electrode and an auxiliary electrode presenting parallel surfaces, an electron emitting electrode between said other electrodes and comprising a plurality of parallel filamentary sections positioned in a surface parallel to said other electrode surfaces and spaced apart a distance at least approximately as great as the distance between said sections and said perforated electrode, a limiting electrode on the side of said perforated electrode opposite said cathode and presenting a surface parallel to said other electrodes, and a source of potential with reference to said electron-emitting electrode for impressing on said perforated electrode a high positive potential, on said limiting electrode a potential approximately that of said cathode, and on said auxiliary electrode a potential sufficiently negative to make the space potential in the plane of said electron emitting electrode and between said electron emitting sections approximately the same as the potential of said sections, and a tuned output circuit including said perforated electrode and another electrode of said tube.
3. An oscillation generator comprising an electron discharge tube having a filamentary thermionic cathode with spaced electron emitting sections side by side in the same plane, a perforated flat anode in front of said cathode and parallel to the plane of said cathode, a cold flat limiting electrode in front of and parallel to said perforated anode and spaced from it substantially the same distance as between said anode and said cathode, a cold flat auxiliary electrode behind and coextensive with said cathode and parallel to the plane of said cathode, a tuned output circuit including said anode, and a source of potential with reference to said cathode for impressing a high positive potential on said anode, a negative potential on said auxiliary electrode to substantially neutralize the field of said anode in the spaces between said cathode sections, and substantially zero potential on said limiting electrode.
4. An oscillation generator comprising an electron discharge tube having a perforated anode, a cold flat front electrode in front of and parallel to said anode, a thermionic cathode with spaced electron emitting sections mounted side by side behind said anode in a plane parallel to said perforated anode and spaced from said front electrode a distance substantially the same as and from said anode a distance no greater than the spacing between said cathode sections, a cold flat backing electrode parallel to said front electrode and behind and overlapping said cath-

ode and the space between adjacent sections of said thermionic cathode, a tuned output circuit connected to said anode and responsive to electron oscillations between said cathode and said anode, and a source of potential with reference to said cathode for impressing a high positive potential on said anode, a negative potential on said auxiliary electrode, and substantially zero potential on said front electrode.

5. An oscillation generator comprising an electron discharge tube having a thermionic cathode with spaced electron emitting sections mounted side by side in the same plane, a perforated anode parallel to the plane of said cathode, a limiting electrode external of and parallel to said anode, a backing electrode positioned to make the potential to the anode of said sections of the cathode and of the interspace between said sections in the plane of said cathode approximately the same, a source of potential with reference to the cathode for maintaining said perforated anode at a positive potential, said limiting electrode at substantially zero potential, and said backing electrode at a negative potential and a tuned output circuit including said anode and one of said other electrodes.

6. An oscillation generator comprising an electron discharge tube having a perforated anode, a thermionic cathode with spaced electron emitting sections mounted side by side in a plane parallel to said perforated anode and spaced from said anode a distance approximately no greater than the spacing between said sections, a limiting electrode mounted external of and parallel to said anode, an auxiliary electrode adjacent said cathode and on the side of said cathode opposite said anode, a source of potential with reference to said cathode connected to maintain said anode at a positive potential, said limiting electrode at a potential lower than that of said anode, and said auxiliary electrode at a negative potential, an input circuit connected to said auxiliary electrode and said cathode, and an output circuit including said anode and said limiting electrode.

7. An oscillation generator comprising an electron discharge tube comprising a flat perforated anode, a straight cathode in a plane parallel to said anode, an auxiliary electrode coplanar with said cathode and comprising two flat strips on opposite sides of said cathode with their edges adjacent said cathode, a limiting electrode parallel to and on the side of said anode opposite said cathode, a source of potential with reference to said cathode for impressing a high positive potential on said anode, substantially zero potential on said limiting electrode, and a low positive potential on said auxiliary electrode, and a tuned output circuit connected to said anode and said auxiliary electrode to respond to electron oscillations between said cathode and said anode.

8. An oscillation generator comprising an electron discharge tube having a thermionic cathode with spaced electron emitting sections mounted side by side, a perforated anode parallel to the plane of said cathode, an auxiliary electrode coplanar with said electron emitting sections, a limiting electrode parallel and on the side of said anode opposite said cathode, a source of potential with reference to said cathode for impressing a high positive potential on said anode, substantially zero potential on said limiting electrode, and a potential substantially the average potential of said cathode sections on said auxiliary

electrode, and a tuned output circuit including said cathode.

9. An oscillation generator comprising an electron discharge tube having a thermionic cathode comprising two straight filaments mounted side by side and connected in parallel, a perforated anode parallel to the plane of said cathode, an auxiliary electrode comprising a metal strip coplanar with said filaments and with its edges adjacent said filaments, a limiting electrode paral-

lel to and on the side of said anode opposite said cathode, a source of potential with reference to said cathode for impressing a high positive potential on said anode, substantially zero potential on said limiting electrode and a low positive potential approximately the average positive potential of said cathode sections on said auxiliary electrode, and a tuned output circuit including said cathode.

BROWDER J. THOMPSON. 10
